JULIUS ALSENZ, OF PALISADES PARK, NEW JERSEY, ASSIGNOR TO THE CUSHMAN & DENISON MANUFACTURING CO., OF NEW YORK, N. Y., A CORPORATION OF NEW YORK.

SELF-INKING STAMP.

1,279,959.

Specification of Letters Patent. Patented Sept. 24, 1918.

Application filed November 30, 1914. Serial No. 874,704.

To all whom it may concern:

Be it known that I, JULIUS ALSENZ, a citizen of the United States of America, residing in Palisades Park, county of Bergen, and 5 State of New Jersey, have invented certain new and useful Improvements in Self-Inking Stamps, of which the following is a specification.

This invention relates to self-inking hand 10 stamps and has particular reference to an improved inking mechanism.

The objects of invention include a simple and positively acting mechanism for causing the movements of the ink distributing 15 means relatively to the printing characters; and further includes the elimination of cams and camming surfaces for the actuation of the inking mechanism.

Referring to the drawings:

20 Fig. 1 is a front elevation of the stamp: Fig. 2, a sectional elevation taken on the line 2—2 of Fig. 1:

Fig. 3, a sectional elevation taken on the line 3—3 of Fig. 4:

25 Fig. 4, a sectional elevation taken on the line 4—4 of Fig. 3: and

Fig. 5, a section taken on the line 5—5 of Fig. 4.

The main casing 10 has located within it 30 the printing frame 11 which is equipped with the usual handle 12 by which it may be depressed, and a spring 13 normally holding it elevated. The frame 11 carries the printing characters mounted in any suitable way.

35 In the present instance the characters are placed upon drums 14, 14, the drums being mounted upon a shaft 15 attached to frame 11 by screws 16, 16. The drums may be rotated about the shaft 15 and suitable spring 40 pawls, as indicated at 17 in Fig. 2, are provided, one for each drum, to prevent their accidental movement and to maintain the alignment of the printing characters. The mechanism thus far described, and its operation, are well known in the art.

The inking means is illustrated in the form of an ink pad 18, and as shown in Figs. 1 and 2, this pad rests normally against the printing characters to supply them with ink, 50 and when the printing frame is depressed in the operation of printing, the pad is swung out of the way to a position indicated by dotted lines in Fig. 4. The mechanism actuating this pad is shown in the form of racks 55 20, 20, one attached to each side of the print-

ing frame 11 by screws 16, 16, and pinions 21, 21 meshing with the respective racks. The pinions are preferably formed integral with arms 22, 22 carrying the ink pad 18, the pinions, arms, and pad all swinging upon 60 stud screws 23, 23 as a center.

As shown in Fig. 4, the downward movement of the frame 11 and the attached racks causes the pinions 21 to rotate, thereby moving the ink pad 18 from the full line to the 65 dotted line position. It will be noticed by this simple gear construction that all cam slots and camming, or compound lever movements, are rendered unnecessary, and that the simple action of the rack upon the pinion 70 is all that is necessary to secure the desired movement. The improved mechanism is not only more simple, more positive, and less liable to get out of order; but it also works with much less friction and wear, as there 75 are no camming or guiding surfaces bearing upon the arms of the ink pad to constrain its motion, such surfaces causing considerable friction and wear owing to the necessary high speed of movement of the ink pad. 80

It is further desirable that the ink pad be withdrawn from contact with the type as soon as the depression of the handle begins. This is provided for in the construction 85 illustrated by giving to the pinions an eccentric pitch line, as shown in Fig. 4, and by giving the racks 20, 20 a slant so that their pitch line is at an angle to the vertical, that is, at an angle to the line of movement of the frame 11. This construction secures an 90 exceedingly rapid movement of the pinions and the ink pad during the first part of the downward movement of the frame and the racks; the movement of the pinions, however, decreasing in speed and extent as the 95 radius of the pitch line of the pinions increases. The slant of the rack is provided to compensate for the eccentric pitch line of the pinions and it is obvious that in the arrangement shown, the pitch line of the racks 100 is always tangent to the pitch line of the pinions at the point where the racks and pinions are in mesh.

The racks are accurately positioned in 105 assembling by means of small stamped up bosses 24, 24 forming dowels which fit into slots 25, 25 stamped in the frame 11. The racks serve also as washers for the screws 16, 16, the screws holding both the racks and the shaft 15 firmly to the frame 11. 110

A further advantage of this construction is that the decreasing range of movement of the ink pad outward due to the eccentric pitch of the pinions results in a more limited final movement of the ink pad. The ink pad swings quickly out of the way of the descending frame 11, but afterward its extent as well as its speed of movement decreases so that it is not moved any farther 10 to one side of the frame than is necessary.

It is obvious that while the invention is disclosed in connection with a dating stamp, it is applicable to all forms of self-inking hand stamps; the inking means may take 15 other form than the pad shown; the printing characters may be mounted otherwise than as shown; and further that the device will operate with a single rack and pinion. The invention is therefore not restricted to 20 the particular type of hand stamp shown, nor is it, by reason of the principle of operation involved limited to the pitch circle of the pinions being eccentric, the essential feature being that the radius of the pitch 25 circle is shorter at the initial acting part of the pinion than at its final part which contacts with the rack.

It is also new, so far as I am advised, to provide a hand stamp in which an inking 30 pad is mounted to oscillate about a horizontal axis and is provided with a series of teeth partially encircling its axis of oscillation and coöperating with a rack having a series of teeth carried by the vertically re- 35 ciprocating frame and engaging the teeth of the inking pad.

I claim:

1. In a self-inking stamp, a frame equipped 40 with printing characters and provided with a rack, ink distributing means including an actuating pinion having a shorter radius, at the active point of initial movement, than at the point of its final movement, the said rack and pinion engaging each other and operat-

ing to impart a quick initial movement and 45 a reduced speed final movement to the inking pad as it is moved away from the printing characters.

2. In a self-inking stamp, a frame equipped 50 with printing characters and provided with a rack, ink distributing means including an actuating pinion, the pinion having an eccentric pitch line, the rack having a pitch line tangent to the pinion pitch line at the point of contact, the said rack and pinion 55 engaging each other and operating to determine the movement of said ink distributing means.

3. In a self-inking stamp, a frame equipped 60 with printing characters, a rack having a pitch line slanting with respect to the line of movement of the frame, guiding studs for the rack whereby it may be positioned upon the frame, ink distributing means including an actuating pinion, the said pinion having 65 an eccentric pitch line and meshing with the said rack.

4. In combination, a frame, a shaft carrying 70 printing drums, screws adapted to attach the shaft to the frame, washers for the screws having an extension forming a rack, the said screws serving to bind the said washers and shaft to the frame.

5. In combination, a frame, a shaft carrying 75 printing drums, screws adapted to attach the shaft to the frame, washers for the screws having an extension forming a rack, the washers being further equipped with means for positioning the washers and racks with respect to the frame, the said screws 80 serving to bind the said washers and shaft to the frame.

In testimony whereof, I have hereunto subscribed my name.

JULIUS ALSENZ.
